United States Patent Office

Des. 176,660
Patented Jan. 17, 1956

176,660

MOTORCYCLE SIDECAR

Roger L. Gamaunt, Redondo Beach, Calif.

Application October 22, 1953, Serial No. 27,278

Term of patent 3½ years

(Cl. D90—8)

FIG. 1.

FIG. 2.

FIG. 3.

Figure 1 is a side elevational view of a motorcycle sidecar embodying my new design;

Figure 2 is a front elevational view of the device; and,

Figure 3 is a rear elevational view of said motorcycle sidecar.

The dominant feature of my design resides in the full line portion of the drawing.

I claim:

The ornamental design for a motorcycle sidecar, substantially as shown and described.
